UNITED STATES PATENT OFFICE

EDWARD THORNDIKE LADD, OF LEWISTON, NEW YORK, ASSIGNOR TO ISCO CHEMICAL COMPANY, INC., OF NIAGARA FALLS, NEW YORK, A CORPORATION OF NEW YORK

FUMIGATING DEVICE

Application filed October 26, 1929. Serial No. 402,613.

My invention relates in general to fumigating devices, and more particularly to a hermetically sealed chest within which garments may be placed for treatment or storage.

The principal object of my invention has been to provide a device so designed that when the cover thereof is closed, a definite charge of liquid or gas will be released within it.

Another object has been to provide a fumigating unit which may be easily removed from the chest for renewal.

Moreover, my fumigating unit is so designed that a standard glass ampoule containing a disinfectant may be used.

Furthermore, the fumigating unit is such that the fluid or gas contained by the ampoule may readily escape from the device, but the broken pieces of glass will be retained in the device, therefore, making it possible to empty the broken ampoule without possible cutting of or injury to the hand.

The above objects and advantages have been accomplished by the device shown in the accompanying drawings, of which:

Fig. 1 shows an enlarged, sectional elevation of the fumigating unit.

Fig. 2 is a sectional view thereof, taken on line 2—2 of Fig. 1.

Fig. 3 is a fragmentary, perspective view of my fumigating chest.

Fig. 4 is a fragmentary, vertical, sectional view, taken through the well for the fumigating unit.

Fig. 5 is an enlarged fragmentary, sectional view showing suitable means for hermetically sealing the cover.

My device comprises a chest 10, of wood or other suitable material, having a hinged cover 11. Suitable means such as a strip 12 of resilient metallic or rubber material may be secured either to the under co-acting edge of the cover or the upper co-acting edge of the chest so as to hermetically seal the joint between the cover and the chest when the cover is lowered.

In one corner of the chest there is provided a well 15 which is preferably formed of a block of wood 16 into which the well is

drilled or bored. The well is provided with a plurality of lateral or upwardly inclined apertures 17 in one or both of the exposed surfaces. The well is of such a size and depth as to receive the fumigating unit 20.

The fumigating unit comprises a casing 21 formed of suitable metal and provided at its upper edge with screw-threads for the screw-threaded reception of a cap 22. The cap 22 slidably carries a plunger 23, having

a foot 24 secured at its inner end, and an operating button 25 secured at its outer end.

The bottom wall 26 of the unit is provided with a central aperture 27 through which the fumigant escapes. A screen 28 is preferably arranged in the bottom of the unit

whereby particles of the broken glass ampoule 29, used with my device, may be retained within the casing 21. Any suitable fumigant may be used in the ampoule, and

depends somewhat upon the treatment to be given the contents of the chest, but I preferably use chlorpicrin.

The parts of the fumigating unit are so proportioned in relation to the depth of the well 15 that the operating button 25 will project upwardly to a position where the cover 11 will cause it to be depressed before such cover has reached its closed position, whereby the device is operated.

Obviously, after the garments to be treated have been placed within the chest, and an ampoule 29 containing the suitable liquid or gas has been placed within the unit, the cap 22 of the unit is screwed down and the

unit is placed within the well 15. The cover 11 of the chest is now closed with a positive pressure which causes the foot 24 carried by the rod 23 to be forced into the upper end of the ampoule, thus breaking the same. The gas produced by vaporization of the liquid will pass through the opening 27 of the casing 21 and out through the openings 17, charging the chest and its contents with vapors of the agent used.

If the garments so treated are to be stored, the chest is, of course, kept closed, whereby the fumigating vapors will be retained within the chest and the garments contained therein. If, however, the garments are to be

treated to disinfect or moth-proof them, they are allowed to remain within the chest for a suitable length of time, after which they are removed from the chest. The fumigating unit is removed from the well and the cap 22 is unscrewed, whereupon the broken fragments of glass may be removed by dumping them out, and without their coming in contact with the hands. A new ampoule may be placed within the body, the cap 22 screwed thereon, and the unit placed within the well.

10 The device is then ready for further use.

15 While I have shown my device as applied to the body of the chest 10, it is obvious that it may be carried in any suitable manner by the cover, and the same advantages derived. This, and other modifications of the details herein shown and described may be made without departing from the spirit of my invention or, the scope of the appended claims, and I do not, therefore, wish to be limited to the exact embodiment herein shown and described, the form shown being merely a preferred embodiment thereof.

20 Having thus described my invention, what I claim is:

25 1. A fumigating device, comprising a chest, a cover for the chest, a fumigating unit carried by the chest, comprising a single-piece, hermetically sealed, breakable container, and means engageable with said container for breaking the same when the cover is moved to its closed position.

30 2. A fumigating device, comprising a chest, a cover for the chest, a fumigating unit carried by the chest, comprising a casing having an outlet opening, a screen disposed over the opening, a glass ampoule contained within the casing and resting upon the screen, a cap for the casing, a slidible plunger carried by the cap having a foot for engagement with the ampoule, and a button carried at the upper end of the plunger for engagement with the cover of the chest when the same is moved to its closed position, whereby the ampoule is broken.

35 In testimony whereof, I have hereunto signed my name.

EDWARD THORNDIKE LADD.
